UNITED STATES PATENT OFFICE.

ALFONSE CALLEBERT, OF JACKSON, MICHIGAN, ASSIGNOR TO REX MACHINE TOOL CO.,
OF JACKSON, MICHIGAN, A CORPORATION OF MICHIGAN.

CYLINDER REAMING TOOL.

1,427,514.

Specification of Letters Patent. Patented Aug. 29, 1922.

Application filed February 2, 1921. Serial No. 441,773.

To all whom it may concern:

Be it known that I, ALFONSE CALLEBERT, a subject of the King of Belgium, residing at Jackson, in the county of Jackson and State 5 of Michigan, have invented certain new and useful Improvements in Cylinder-Reaming Tools, of which the following is a specification.

This invention relates to a cylinder reaming 10 jig and tool. Automobile engine cylinders have to be often re-bored due to scoring and other causes. It is the object of the present invention to provide an improved guide for the tool and also to provide an improvement in the withdrawal of the reaming 15 cutter from the cylinder, as will presently be described.

In the drawings,—

Fig. 1 is an end elevation of the cylinder 20 showing the tool and jig mounted for work.

Fig. 2 is a plan view of the same.

Fig. 3 is a vertical cross section of the tool and jig.

Fig. 4 is a section on the line 4—4 of 25 Fig. 3.

Fig. 5 is a section on the line 5—5 of Fig. 3.

Fig. 6 is a section on the line 6—6 of Fig. 3.

30 *a* designates the cylinder block which reaches to at about the height of the upper limit of the piston travel and a cover or cylinder block cap is ordinarily bolted onto the block. This is not shown. The jig com-

35 prises an upright hollow cylinder *b* which is intended to act as a guide for the tool body *c*. This guide is cut away at *d* to lessen its weight. The guide is a casting which has laterally spreading feet or a frame *e* which

40 permits the same to rest on the top of the cylinder block to which it may be clamped by bolts fastened into the cap screw sockets of the cylinder block. The purpose of the guide *b* separate from the tool body *c* is to

45 permit the jig first to be properly set upon the cylinder block. The jig and the tool are arranged to re-bore cylinders of varying diameters within given limits. It is, therefore, absolutely necessary to properly center 50 the jig upon the cylinder bore. This is accomplished by first putting the jig on the top of the block and then using a centering piston in the guide, that is, a piston with a tapered lower end that can be brought down

55 into the top of the bore to center the jig

upon the bore. The jig may then be clamped in place, the centering piston withdrawn, and the tool body *c* put into the jig in place of the centering piston.

This tool body *c* is provided with a flange 60 *f* to hold it on the top of the guide of the jig. A continuation of this body *c* in the form of a long depending sleeve *g* forms a guide for the reaming cutter *h*. This reaming cutter comprises a plurality of inserted 65 tool steel blades *k* carried in the split collar *l* and held in place by the pins *m* driven in the splits in the collar. This collar screws onto the upper end of the outer sleeve *n*. The lower end of this outer sleeve has a plug 70 *o* threaded into it which is provided with a square opening *p*. The outer sleeve *n* will be designated the tool-carrying sleeve and the inner sleeve the guide sleeve. Obviously 75 these two sleeves closely fitting together and being as long as they are form a very accurate guide extending clear down into the cylinder itself directly at the point where the resistance is brought upon the cutter. Heretofore, as I am informed, it has been 80 the practice to carry the reaming tool on a shaft or arbor, which is guided only at its upper end in the tool body.

The outer sleeve is driven by means of 85 the arbor *q*. The load of the reaming tool is carried on the guide sleeve *g*. The arbor *q* is a divided arbor, having two parts screwed together at *r*. This makes the arbor convenient to carry.

The upper arbor portion is screw-threaded 90 as at *s* for the purpose of rotating and advancing the reaming tool into the work. Now obviously with an ordinary nut to receive the threaded portion of the arbor one has to tediously turn the arbor in order to 95 withdraw the same from the body of the tool. This I obviate by using the split nut *u* in connection with the divided arbor. After the boring has been completed, the lock nut *t* is removed, as is also the nut *v* on the 100 lower end of the arbor, and thereupon the arbor together with the split nut *u* may be lifted right out of the cavity in the top of the body. It will be noticed that the cavity for receiving the nut is tapered, as 105 is also the nut. The consequence is that the nut may be applied to the threads on the outside of the arbor. The arbor and the split nut may then be dropped into the cavity and the lock nut *t* can then be turned 110

in against the two portions of the split nut, driving the tapered split nut into the tapered cavity to bring the two parts tightly together and the threads of the split nut tightly upon the threads of the arbor. In other words, the tapered arrangement of the cavity and nut forms a very nice guide for the loose parts as they are dropped in place, and the lock nut t in connection with this 10 tapered arrangement serves to drive all the parts into suitable relationship. As will be apparent from Fig. 4, the split nut is provided at one side with a space or key-way w which permits the pin x to prevent the 15 nut from turning.

I have found it convenient to provide slotted ears y on the flange f on the body of the tool, into which may be swung the hinged screws z that are hinged to the jig. This permits 20 these screws to be swung up into the slots of the ears and the wing-nuts 1 turned down to clamp the body of the tool onto the jig.

What I claim is:

1. In a tool for the purpose specified, the 25 combination of a body, a hollow guide sleeve depending from the body, a cutter-carrying sleeve rotating on said guide sleeve, a cutter carried on the sleeve, and means for driving the cutter-carrying sleeve, said means extending through the hollow sleeve and engaging the end of the cutter-carrying sleeve remote from the said body.

2. In a tool for the purpose specified, the 35 combination of a body, a sleeve depending from the body, a driving arbor within the sleeve, and a cutter supported and guided on the outside of the sleeve, the said arbor extending through said sleeve and out the 40 end of the sleeve remote from the body and connected at such end with the cutter.

3. In a tool for the purpose specified, the 45 combination of a body, a guide sleeve depending therefrom, a cutter carrying sleeve guided in rotation and in axial movement on the sleeve, a cutter thereon and an arbor for rotating and advancing the cutter, the said arbor secured within the said guide sleeve and connected with the cutter-carrying sleeve at the end remote from the body.

50 4. In a tool for the purpose specified, the

combination of a body, a sleeve depending from the body, a cutter-carrying sleeve supported slidably and rotatably on the outside of the guide sleeve, a cutter carried on said cutter-carrying sleeve, and an arbor carried within the guide sleeve and serving to rotate and advance the said cutter and having a detachable but driving connection with said cutter-carrying sleeve.

5. In a tool for the purpose specified, the 60 combination of a body, a guide sleeve depending from the body, a cutter-carrying sleeve rotatable and slidable on the outside of the guide sleeve and provided in its end with a plug having a polygonal opening, a 65 cutter carried on said cutter-carrying sleeve, and an arbor rotatable in the guide sleeve and serving to rotate the cutter-carrying sleeve and also advance the cutter, said arbor being provided with a polygonal end 70 that may be fitted in the polygonal opening in the said plug.

6. In a tool for the purpose specified, the combination of a body provided with a cutter guide, a cutter, an arbor having a threaded portion and arranged to drive the cutter in rotation and advance the same, a split nut for advancing the arbor by engaging the threads thereof, and means for detachably securing the split nut within the body 80 to permit the arbor to be withdrawn from the body without turning.

7. In a tool for the purpose specified, the combination of a body, a guide sleeve depending therefrom, a cutter-carrying sleeve 85 slidably and rotatable on the outside of the guide sleeve, an arbor having an upper threaded portion and a lower portion provided with an end adapted to fit into driving relation with the cutter-carrying sleeve 90 but removable therefrom, and a split nut detachably fitting into the said body of the tool by which the arbor is guided in advancing the cutter upon the work but which may be released from the body to permit 95 the separation of the arbor from the cutter-carrying sleeve and the withdrawal of the arbor by longitudinal movement.

In testimony whereof I affix my signature.
ALFONSE CALLEBERT.
